UNITED STATES PATENT OFFICE.

CHARLES WEISS, OF NEW YORK, N. Y.

DESIGN FOR A HANDLE FOR A CUP OR SIMILAR ARTICLE.

Application filed January 22, 1929. Serial No. 29,727. Term of patent 7 years.

To all whom it may concern:

Be it known that I, CHARLES WEISS, a citizen of the United States, and resident of the borough of Manhattan, city, county, and State of New York, have invented a new, original, and ornamental Design for a Handle for a Cup or Similar Article, of which the following is a specification, reference being had to the accompanying drawing, forming part hereof, in which—

Fig. 1 is a side elevation of a handle, and Fig. 2 is a front elevation of a handle illustrating my new design, the dot and dash outline indicating diagrammatically a cup with which the handle is adapted to be associated.

I claim:

The ornamental design for a handle for a cup or similar article, as shown, and described.

CHARLES WEISS.
